UNITED STATES PATENT OFFICE.

JAMES HADCOCK AND WILLIAM HENRY NAYLOR, OF LEEDS, ENGLAND.

LABELING AND LIKE MACHINE.

1,332,625.

Specification of Letters Patent.

Patented Mar. 2, 1920.

Application filed February 1, 1916. Serial No. 75,505.

To all whom it may concern:

Be it known that we, JAMES HADCOCK and WILLIAM HENRY NAYLOR, residing, respectively, at North Inch, Shaftesbury avenue, 5 Roundhay, Leeds, in the county of York, England, and 4 Kings Place, Headingley, Leeds, in the county of York, England, have invented new and useful Improvements in or Connected with Labeling and like Machines, of which the following is a specification.

This invention relates to improvements in or connected with labeling machines, and it is particularly applicable for applying a 15 label to the end of a packet, or box, or article to which end labels are applied, all of which are hereinafter termed and included in the term "packet". The hereinafter described machine or apparatus may be used 20 either separately or in combination with a packaging machine.

Hitherto great difficulty has been experienced in applying the labels to the ends of packets owing to the ear or fold at the 25 end of a filled bag being liable to spring open before the mucilage or other adhesive material,—that has been applied to the end label,—has had time to become partially set or dried.

30 In this invention provision is not only made for gumming and feeding the label into position, but means are also provided for feeding the packet into position for receiving the label, applying the label to one 35 or to both of its ends simultaneously, and holding the label in position until the mucilage or other adhesive material has had time to become partially set or dried, and finally to eject the packet from the labeling 40 machine.

According to this invention on a suitable table mounted upon a pillar, or standard, or framework,—all of which are hereinafter termed "framework",—is mounted the driving shaft and operative parts of the machine. On the table is fixed the gumming 45 apparatus, and a second set of framework in which is mounted a rock shaft carrying swinging arms provided with gum and striping pads, for each label. The gum pad first passes over a gumming roller for receiving a film of mucilage and then takes up 50 a label from a box or magazine fixed at an angle to the table. The packets to be la-

beled are either placed vertically,—that is 55 on their ends,—in a U-shaped trough when used in combination with a packaging machine and subsequently turned into a horizontal position by a lever transporting arrangement and an oscillating curved guide 60 plate to be hereinafter described, or they are placed in a vertical chute directly over the pockets formed for their reception in an intermittently rotating drum, or on an endless belt. The pockets are slightly less in length 65 than the packets to be end labeled. The pockets are provided at one or both of their ends with a spring controlled frame, herein-after termed "a cage" and spring controlled bottom plate,—which fits within the cage,— 70 provided with a hole in its center. The cages and bottom plates are hinged to the said drum, and the labels to be applied to the ends of the packets are deposited by the gum pads in the cages. The cages and bot- 75 tom plates are arranged at certain stages of the intermittent rotation of the drum to be automatically opened or closed. The cages and bottom plates first press the ends of the packet in one position, then the drum is 80 made to rotate with the cage and end plate closed on to the packet, and at another position, the cages and bottom plate open for receiving the label and applying it to the packet, after which the drum will be suc- 85 cessively moved until the packet reaches the point for it to be automatically ejected from the pocket into or on to a chute for conveyance to any desired place.

In the drawings hereunto annexed is 90 shown mechanism for achieving these objects, and for carrying this invention into practice, in which—

Fig. 1. is a side elevation of the end labeling machine combined with a packaging 95 machine, and with the label box removed;

Fig. 2. an elevation of the right hand end of Fig. 1;

Fig. 3. an elevation of the left hand end 100 of Fig. 1;

Fig. 4. a side elevation of the opposite side of the machine shown at Fig. 1, and with the packaging machine removed;

Fig. 5. a side elevation of end labeling machine having a vertical packet feed;

Fig. 6. an end elevation of the same;

Fig. 7. a part side elevation of an end labeling machine with an endless belt feed;

- Fig. 8. a part end elevation of the same;
 Fig. 9. an enlarged elevation of the gripping fingers;
 Fig. 10. an enlarged side elevation of the same;
 Fig. 11. an enlarged plan of Fig. 9;
 Fig. 12. an enlarged end elevation of the cage, bottom plates, and their operating mechanism;
 10 Fig. 13. an enlarged side elevation of Fig. 12;
 Fig. 14. a further enlarged elevation of the bottom plate;
 Fig. 15. a further enlarged sectional elevation on line A, B, Fig. 14;
 Fig. 16. an elevation of mechanism for transferring a packet from ejector trough of the packing machine to the feeding platform of the end labeler.
 20 The single and separate machine will be first described, and afterward how it may be combined with a packaging machine, and the modifications, and alterations,—such as, for example, the transference of certain parts from one machine to the other,—that are necessary. As far as possible like parts in all the views, and in both machines, will be marked with similar letters of reference, but where necessary, and in order to 25 avoid confusion, a numeral will be added to the letter of reference in a transferred and equivalent part of the combined machine.
 At Figs. 1 to 4 the table *a* of the machine is mounted upon a pillar, or standard, or 30 framework, all of which are hereinafter termed and included in the term “the framework *b*”. In the drawings a standard is shown, and on it is provided or fixed thereto bearings for the driving shaft *c*. On 35 the driving shaft is mounted or fixed the fast and loose pulleys *d*, *e*, bevel gearing *f*, chain or sprocket wheel *g*, cams *h*, *i*, *j*, *k*. A shaft *l* is carried and fixed in bosses on the framework *b*, and on it are loosely 40 mounted so as to oscillate freely the cam levers *m*, *n*, *o*. A cam lever *p* is carried by a bracket *q* fixed to the table *a*. A cross shaft *r*,—mounted in bearings on a bracket *s* (Figs. 5 and 6),—is connected to the driving shaft *c* by bevel gearing *f*. On the shaft *r* is fixed a bell cam *t*. On the top of the 45 table *a* is mounted the gum box *u* in which is made to rotate the roller *v* for taking up the mucilage.
 50 A rotary motion is imparted to the gum roller *v* from the sprocket wheel *g*, endless chain *w*, sprocket wheel *x* carried on stud fixed to the frame *b*, and attached to sprocket wheel *x* is a spur pinion *y* (Fig. 3) 55 which gears into a spur wheel *z* fixed on the spindle of the gum roller *v*.
 To the table *a* is or are also fixed one or 60 more labeling receiving boxes or magazines, hereinafter termed the “magazine 1”, which 65 is or are fixed at an angle to the said table.

On the top of the table is also mounted framework *2*, *2* in the form of standards. When desired the frameworks *b* and *2* may be made in one casting, and in the upper end of the framework *2* is mounted a rock shaft 70 3 which is intermittently oscillated by lever 4 fixed thereto, connecting rod 5 (Fig. 5), lever *m* provided with a runner or bowl 6 which is arranged to engage with a bell cam *j*. On the rock shaft is or are mounted one 75 or more,—say two,—cams 7, 7 for operating one or more gum pads 8, 8. The gum pads 8 are mounted in the swinging arms 9 by spindles 22. The swinging arms are mounted so as to oscillate freely on the rock 80 shaft 3.

An intermittent oscillating movement is imparted to the arms 9 from cam *i*, runner 10, spring controlled lever *n* and connecting rod 11, which is attached to arm 9, as shown 85 at Figs. 1 and 2.

Working in conjunction with each gum pad, and carried by the arm 9, is a label stripper 12 which is made,—though not necessarily so, in the inverted U-shaped 90 form (shown at Fig. 1) and connected to the vertical spindle 13 which passes through the boss provided for its reception in the swinging arm 9. The stripper 12 is intermittently acted upon by cam shaped lever 95 14 mounted upon a stud 15 fixed to the framework 2. The required oscillating movement is imparted to the cam lever 14 from segment cam 16 fixed to the side of cam *i*, bowl or runner 17 on one end of 100 doubled ended lever 18 mounted upon stud 19 (fixed to the framework *b*) connecting rod 20 and lever 21 mounted upon the same stud 15, or made to form part of the cam lever 14. The spindles 13 and 22 are provided at their upper ends with runners or bowls 23, and 24, and the runners are kept in contact with their respective cams by means of the springs 25 and 26 (Fig. 1).

On shaft 27, carried in suitable bearings 110 formed for its reception on the framework 2, is mounted a circular drum 28 provided with a number of transverse pockets or recesses 29 in its periphery for receiving the packets 30 to be labeled. Each pocket 29 is 115 open at one side for receiving a packet 30, and it is slightly shorter in length than that of the packet to which the end labels are to be applied, and it is shaped to suit the contour of the packet. One or both ends of the 120 pockets are also left open, and they are closed as required by a spring controlled square or rectangular, or other shaped frame or receptacle, hereinafter termed a “cage 31.” When the pockets 29 are open 125 at both ends then a cage 31 is jointed to the drum at each side thereof, but when only one end of a pocket is open, then only one cage is employed, and the other end of the pocket is either filled by the side of the 130

drum or by an end piece being fixed thereto. Within each cage 31 and also jointed to the drum is what is termed a spring controlled bottom plate 32 provided with a 5 hole 33 in its center. The bottom plate 32 is made of such a thickness as to permit of the sides of the cage 31 projecting above its upper surface so that the cage 31 forms a receptacle for the label which is deposited 10 therein by the gum pad 8.

The bottom plate 32 is fixed by the boss 35 to the spindle 36 which is carried in a bearing 37 fixed to, or forming part of, the drum 28. On the spindle 36 is also fixed a 15 lever 38 having a bowl or runner 39 mounted upon its free end and which is kept in contact with the cam path 40 by means of spring 41. The tension of the spring 41 is adjusted by a collar 42 mounted upon one 20 end of the spindle 36. The cage 31 and bottom plate 32 are connected together by a spring 43,--mounted upon spindle 36,--so as to move together for a portion of their oscillation.

25 The cam path 40 is formed on the rim of plate 44 and at a right angle thereto, and is mounted loosely so as to oscillate freely upon the shaft 27, and the said rim is provided with one or more recesses 138, 139,--two of 30 which are shown at Fig. 12,--in order to independently operate the cage 31 and bottom plate 32, so as to turn the two said parts from an open into a closed position, or vice versa, during the intermittent rotation of 35 the drum 28. An oscillating cam 40 is provided for each set of cages and bottom plates, and provision may be made, when required, for adjusting the cams horizontally inward or outward for increasing or decreasing the pressure of the bottom plate upon the end of the packet when applying a label thereto. The said adjustment may be accomplished by moving the collars 116 inward or outward on shaft 27. Attached 40

45 to cam 40 is an arm 45 to which is imparted an intermittent oscillating movement from cam *h*, runner 47, lever *o* and connecting rod 46. When a cage 31 and bottom plate 32 are provided for each end of a pocket 29 50 then the two arms 45 of cams 40 are connected together by the end of rod 46, which is made of such a length as to pass between them,--as shown at Fig. 5,--and to be secured in position by the bolt 48. The face 55 of the bottom plate 32 that comes in contact with the end of the packet is either made level or it may be stepped, as shown at Figs. 14 and 15. That is to say when it is stepped its face is made on a different level 60 to accommodate the varying thicknesses of end folds 80, 81, 82, and 83. In the bottom plate 32 is also a recess 84 in which one edge of the cage 31 passes. When the cage 31 and bottom plate 32 are in the open position 65 for receiving a gummed label the bottom

plate 32 is arranged to pass over a vertical pin 85 which is fixed to the table *a*, and which passes through the hole 33 and slightly projects above the surface of the bottom plate 32. The fixed pin is, when 70 required, provided with a collar or projection,--not shown in the drawings,--upon which the bottom plate 32 may rest. On one or more sides of the cage 31 is or are formed one or more recesses through each 75 of which passes an oscillating finger or gripper 86 or 87, mounted respectively on a rock shaft 88,--carried in suitable bearings or brackets 89 fixed to the table, or upon a stud fixed to said brackets. The grippers 80 86, 87 are employed for holding the label on to the bottom plate 32.

An intermittent oscillating motion is imparted to the grippers from cam *h*, runner 91, mounted on cam lever *p* mounted upon 85 spindle 92,--carried by bracket *q* fixed to table *a*,--lever 94, connecting rod 95, lever 96 fixed on spindle 88.

Motion is simultaneously imparted to the grippers 87 from spindle 88 through levers 90 97 fixed thereon, links 98 and levers 99 forming part of the grippers 87. The grippers 87 are first moved into action and to provide for the necessary pressure and compensating movement while the grippers 86 are being brought to their work, springs 100 are mounted in the recess formed for their reception in each link and are arranged to act upon pins 101 fixed to levers 99, the hole in the link being elongated to permit of such 100 movement. The runner 91 is retained in contact with cam *h* by means of a spring not shown in the drawings. A peg or plunger 102 is fixed to each portion of the U-shaped stripper 12 and is arranged to work through 105 a hole in the gum pad for holding the central portion of the label on to the end of the vertical pin or projection 85 while the gum pad is being raised.

An intermittent rotary motion is imparted 110 to the drum from a runner 49 (Fig. 3) fixed to the sprocket wheel 50, over which the endless chain *w* passes. The runner 49 is made to engage with the radiating slots 51 of a star wheel or plate 52 fixed upon shaft 27. The 115 number of slots 51 correspond with the number of pockets 29 in drum 28. Fixed to the side or face of the sprocket wheel 50 is a cam 53 which is made to act upon a runner 54 fixed to an oscillating lever 55 mounted 120 upon stud 56 fixed to the framework *b*. At or near the end of lever 55 is mounted a second runner 57 arranged to engage with one of the radiating slots 51 and to act as a stop for retaining the drum in a stationary 125 position.

In some cases it may be preferred to employ a ratchet wheel, pawl, and lever in place of the said roller and cam.

The packets to be labeled are placed in a 130

vertical chute 58 (Figs. 5 and 6) which is fixed to the framework 2 above the intermittent rotating drum 28; or, if desired, the chute 58 may be arranged at such an angle 5 that the packets 30 will fall by gravity first on to the periphery of the drum 28 and then pass into a pocket 29 when the latter is turned into a position to receive it.

For the vertical or angular gravity feed 10 the pockets 29 are made slightly less in depth than the thickness of the packet. By this means the packet in a pocket holds a succeeding one clear of the periphery of the drum until the said periphery has been sufficiently turned to support it. Or, when desired, the packets 30 are placed by hand transversely on a traveling endless belt 59 (Figs. 7 and 8). The endless belt 59 is mounted upon pulleys 60, 61. The required 20 intermittent traveling motion is imparted to the traveling belt by means of ratchet wheel 62 fixed to the spindle 63 of pulley 60 carried in bracket 64 and the endless belt is kept taut by pulley 65 mounted upon one end of 25 a weighted bell crank lever 66 loosely mounted upon spindles 63. On spindle 63 is also loosely mounted a lever 67 to the free end of which is jointed a pawl 68 which engages with the teeth of ratchet wheel 62. Lever 30 67 is attached by connecting rod 69 to a lever 70 mounted upon a shaft 71. On the shaft 71 is a curved lever 72 which is connected by rod 73 to arm 45 of cam 40.

At the inner end of the endless belt 59 is 35 a stop 74 against which the packets are brought by the belt. As soon as a packet is brought against the stop 74 it is moved transversely by a plunger 75 mounted upon a rod 76 attached to an arm 77 which slides upon 40 guide rods 78 and is fixed upon sliding rod 79 so as to be intermittently reciprocated by cam *t*, as will be presently described for the ejecting movement.

At the inner end of the endless band 59,— 45 but on one side thereof—is fixed a curved plate or platform 135 on to which the packet is pushed by the plunger 75, and the means for transferring it from that plate into a pocket will be fully described when the end labeler is combined with a packaging machine.

The packets 30 are ejected from the pockets 29 when the drum 28 is at rest, and has reached the position III. An ejector plunger 103 forming part of, or fixed to arm 104 is mounted upon the guide rod 78 and sliding rod 79. The required intermittent reciprocating motion is imparted to the ejector plunger from bell cam *t*, runner or bowl 105, lever 106, fulcrumed to stud 107, fixed to framework *b* (Figs. 5 and 6) and connecting rod 108 which is attached to the ejector 104. The ejector removes a packet 30 from a pocket 29 on to an oscillating platform 60 109,—which is then in a horizontal posi-

tion,—fulcrumed to the trough or chute 110. The platform 109 is connected by a lever or arm 111 and link 112 to a spring controlled sliding rod 113 carried by a bracket 114 fixed to the table *a*¹, or framework *b*. On the return stroke of arm 104 it comes in contact with a tappet arm 115 fixed upon the spring controlled rod 113 which causes the platform 109 to be turned into the vertical position shown at Fig. 5 for aiding in pressing the 75 label on to the folded portions of the end of the packet, the label on the other end being held in position by a previously ejected packet.

Before describing the action of the above 80 machine the necessary modifications and alterations for combining it with a packaging machine will now be described, as the action is common to both machines, the chief difference being the feeding of the packet 85 to the pockets.

At Figs. 2 and 3 are shown portions of a packaging machine combined with the end labeler, in which *a*¹ is the table of the packaging machine mounted upon the standard 90 or framework *b*¹. In this arrangement the fast and loose pulleys *d*¹, *e*¹ are mounted and fixed respectively upon the driving shaft *c*¹ of the packaging machine. On the said shaft is also mounted the bevel gearing *f*¹, *f*¹ 95 which is transferred from shaft *c* of the end labeler to shaft *c*¹ of the packaging machine. Cross shaft *r*¹ mounted in brackets *s*¹ is then arranged to work in conjunction with the packaging machine and an additional 100 sprocket wheel 117 is then mounted upon the shaft *r*¹ partially around which the endless chain *w* is made to pass. Owing to the extended length of the endless chain a tightening arrangement is provided consisting of a 105 sprocket wheel 118 mounted upon a double ended lever 119 fulcrumed upon stud 120 and adjusted by the eye-bolt 121 fixed at one end to the short arm of lever 119, and at the other end arranged to pass through a 110 lug or projection 122 fixed to the framework *b*. The eye-bolt 121 is provided with a nut 123 for retaining it in position. As the short arm of the bell crank lever 119 is moved to or from the lug 122 the sprocket 115 wheel 118 will be raised or lowered for tightening or slackening the chain. In this arrangement the bell cam *t* and lever 106 are also transferred to the packaging machine, and the said cam is mounted upon 120 shaft *c*¹, and in this case the lever will be fulcrumed upon the said rod 124 of the packaging machine.

125 is the ejector trough of the packaging machine which is mounted, as usual, above 125 the table *a*¹. In the end of the ejector trough 125 is a recess in which is mounted a packet receiving cage or hooked shaped lever 126, Figs. 2, 3, and 16. That is to say a portion of the lever is removed to form a recess so 130

that the packet is held therein by its two ends and one side and also by inwardly projecting lips 127 formed upon the open or mouth side of the recess. The said lever 5 is mounted upon a rock shaft 128 which is mounted in suitable bearings attached to the chute 125, or, if necessary, may form part of a bracket 129 fixed to the table α^1 .

An intermittent oscillating movement is 10 imparted to the rock shaft 128 and hooked shaped lever 126 from cam 130 mounted on shaft ϵ^1 , runner 131 mounted upon lever 132, connecting rod 133 and lever 134 fixed to the rock shaft 128.

15 The packets to be end-labeled are delivered from the packaging machine into chute 125 on their ends,—that is in a vertical position,—and after being pressed forward by the ejector plunger of the packaging machine,—not shown in the drawings,—they enter the recessed hooked portion of lever 126. On an oscillating motion being imparted to the said lever it is turned from the vertical into a horizontal position with 20 its open mouth downward which brings the side of the packet over the curved plate or platform 135 which is fixed to, or forms part of, bracket 129 ready to be pushed from the recess on to the curved plate or platform 25 135.

30 In the curved plate or platform is or are formed one or more slots at a right angle to the path of oscillation of lever 126. Through the slots in the curved plate or 35 platform 135 are arranged to pass the free ends or prongs,—which form transporting levers,—of plate 136 which is fixed to an oscillating lever 70 mounted upon a rock shaft 71, which, in this instance, is carried 40 by bearings in the bracket 129.

The rock shaft 71 is operated as previously described by cam h for the single and separate machine.

When the packet 30 is over the curved 45 platform 135 the transporter ends of plate 136 are in a vertical position on the packaging machine side of the packet, and as the said plate is moved toward the end labeling machine it carries the packet with it out of 50 the recess in the hooked lever 126 on to the curved platform 135 and into a pocket 29, as shown at Fig. 2. The packet after it is deposited in a pocket is free to be acted upon by the cage 31 and bottom plate 32.

55 In place of bracket 114 (Fig. 5) of the single machine a bracket 137 (Fig. 3) is fixed to table α^1 , and it is employed for supporting the guide rods 78, 79. The ejector plunger 103 is attached to the bracket 104 which slides upon the guide rods 78 and is fixed to the sliding rod 79, and motion is imparted to it from cam t , as in the single 60 machine.

In some cases it may be found advisable to 65 make the drum 28 in two portions (as shown

at Fig. 5) and to fix the pockets,—which are also made in two portions,—to the peripheries of the arms or divided pulley. By this means provision is made for adjusting the drums and pockets to different 70 lengths of packets. The two portions of the drum are retained in position by means of screws 140.

The action of the machine is as follows:—

The labels are placed in the magazine 1 75 which is provided with means,—not shown in the drawings,—for keeping them at a pre-determined level. On the machine being set in motion the gum pads will be moved over the gum roller v by which a 80 film of gum will be transferred to the pad, and when the gum pads have reached the label magazine 1 they are depressed outward by the cam 7 on to the labels, and as soon as the runners in the end of the gum 85 pad spindles have passed over the projections the pads, with the label adhering thereto, are raised by their springs clear of the end of the label magazine 1, and on the return stroke of the gum pads,—which are 90 then clear of the roller v ,—they are carried and brought to rest over a cage 31 and bottom plate 32 for depositing it into the said cage at position II. In this position the cage 31 and bottom plate 32 will be in their 95 open position and over fixed pin 85, as shown at Fig. 10. The gum pads are pressed down into the cage by the projection on cam 7. When in this position the gripper fingers 86, 87 are then turned inward as previously described. At or about the same time that the gum pads descend into the cage 31 the stripper 12 is moved downward by cam lever 14 which also brings the pins or pegs 102,—which grip the labels,—on to the ends of fixed pins 85. As soon as this is accomplished the gum pads rise and when they have reached their top position the stripper is withdrawn leaving the label held down on to the bottom plate 110 by the gripper fingers 86 and 87. The gripper fingers are afterward moved clear of the plate. The packets 30 are fed by hand into the vertical chute 58 and from which they are passed into a pocket 29 as previously described when the rotating drum is in position I. Or, the packets are placed by hand upon the traveling band 59 (Fig. 7) from which they are transferred,—as previously 115 described,—on to the curved platform 135. 120

Or when the end labeler is fed direct from a packaging machine then they are placed in the hooked lever 126 and turned over so as to be delivered on their sides on to the curved platform 135 and by the oscillating 125 lever 70 and transporter ends of plates 136 are moved over the said platform into a pocket 29 when the drum has been turned and is at position IV. When a packet 30 enters a pocket 29 the cage 31 and bottom 130

plate 32 will be in an open position, and when the drum 28 commences to rotate the cage 31 and bottom plate 32 are closed on to the ends of the packets 30 for pressing the 5 folded end portions thereof together and for registering the packet for labeling, and at the same time insuring that the ears or folds shall be securely held in position thereby preventing the contents of the packet 10 escaping while it is traveling into position II for receiving the label. The drum is intermittently rotated until position II is reached when the runner 39 will have passed off the rim of cam 40 into the recess 139 which permits of the cage and bottom plate 15 being in the open position for receiving the label as previously described. As soon as the gum pad is swung clear away to take up a label from the label magazine 1 the cage and bottom plate are turned by the 20 oscillating cam 40 into the closed position for applying the label to the end of the packet. When the spring cage 31 reaches the packet the latter is gripped by it while the bottom plate 32 continues its inward 25 movement for placing the label in position and causing it to adhere thereto. The drum 28 is then caused again to rotate for bringing another carrier and bottom plate into 30 position for receiving another label. The label is held firmly in position on the end of the packet so long as the runner 39 remains on the rim portion of cam 40, and as soon as position III is reached the runner 35 39 will have passed into a recess 138 of cam 40 for again turning the cage and bottom plate into an open position, and also for allowing the packet 30 to be transferred by the ejector 103 from the pocket to trough 40 or chute 110, and from thence to where required. The cage and bottom plate remain open until the pocket in the drum has traveled to the next packet receiving position, when the cycle of operations will be again 45 repeated.

What we claim is:—

1. In a machine for applying labels to the ends of packets, framework having a table fixed thereon, a driving shaft carried in 50 bearings on said framework having the operative parts of the machine mounted thereon, a gum box and roller fixed upon the said table, a second set of framework having a rock shaft mounted thereon, swinging arms 55 provided with gum and stripping pads carried by said arms and means for oscillating the said shaft, a box containing labels, said box being arranged at such an angle that the labels will come in the path of the swinging 60 arms, a trough for conveying the packets to be labeled, a transporting lever, an oscillating curved guide plate, and an intermittently rotating drum having a number of pockets 65 therein as set forth, means for actuating the said transferring lever, means for rotating

said drum and means carried by the drum for affixing the labels to the packages carried in the pockets of said drum.

2. In a machine for applying labels to the ends of packets, the combination of framework having a table mounted thereon, a gum box fixed to the said table, a second set of framework, a rock shaft mounted in bearings on the second framework, oscillating arms provided with gum and stripping pads 70 fixed thereon and means for operating the said rock shaft, gum and stripping pads, a label receiving box and parts connected therewith fixed on the table, an intermittently rotating drum having a plurality of 75 pockets formed in its periphery, spring controlled cages in frame form hinged to the ends of the drum having spring controlled bottom plates working therein and provided with holes in the center for receiving the 80 labels as they are deposited by the gum pads, means for opening and closing the cages and bottom plates at pre-determined stages of the rotation of the drum and for pressing the ends of the packets in one 85 position, then rotating with the drum to the next stage, again opening to receive the label and being closed again for applying it to the packet after which the cage and bottom plate will be again opened and means 90 for ejecting the packet from the drum, and troughs for conveying the packet to the drum and receiving it after a label has been 95 applied as set forth.

3. In a machine for applying labels to 100 the ends of packets, the combination with an intermittently rotating drum having a pocket therein, means for intermittently rotating the drum, a spring controlled cage in frame form hinged to the end of the drum 105 opposite the pocket and having a spring controlled bottom plate fitting therein, a spindle upon which the cage and bottom plate are mounted having a lever provided with a bowl carried thereon, an oscillating cam 110 plate and means for operating the same for opening the spring cage and bottom plate at each stage of the intermittent rotation of the drum as set forth.

4. In a machine for applying labels to 115 the ends of packets, an intermittent reciprocating drum having a number of pockets formed therein for receiving the packets to be labeled, means for conveying the packets successively and placing them in the pockets of the drum, spring controlled cages each having a bottom plate working therein hinged to the drum opposite each pocket for closing the ends of the pocket, means for simultaneously opening and closing the 120 cages and bottom plates and for imparting pressure separately to them for applying the labels to the ends of a packet and holding them thereon until the packet reaches the 125 delivery stage when the cages and bottom 130

- plates are again opened, means for supplying a gummed label to each cage in succession and for intermittently rotating the drum, and for ejecting a labeled packet from 5 a pocket as set forth.
5. In a machine for applying labels to the ends of packets, the combination of framework having a table mounted thereon, a rock shaft carried in bearings, swinging 10 arms mounted thereon having gum and stripping pads attached thereto, means for oscillating the arms and operating the pads, a gum box mounted upon the table provided with a roller over which the gum pads 15 work in their outward movement, a label receiving box fixed at an angle to the table and with its mouth in the path of the outward movement of the gum pad, a rotating drum having a number of pockets formed 20 at regular distances apart, said pockets being slightly less in length than the packets and open at their ends, label receiving cages and centrally perforated bottom plates arranged within the cages and hinged to the 25 drums opposite the ends of the pockets, each of said cages and bottom plates being capable of being opened and closed simultaneously and having pressure applied thereto separately, an oscillating cam for independently operating each of the said cages and bottom plates and means for ejecting the 30 packet from the pockets as set forth.
6. In a machine for applying labels to the ends of packets, the combination of framework having a table mounted thereon, a second set of framework having bearing for a rock shaft, means for actuating the rock shaft, swinging arms mounted thereon provided with gum and stripping pads at their 35 lower ends, means for operating the said pads, a gum box having a roller rotating therein, a label receiving box fixed at an angle to the table, an intermittently rotating shaft carried in bearings on the framework, an intermittently rotating drum 40 mounted upon the said shaft so as to rotate therewith, pockets in said drum, said drum being made in two halves and means for adjusting the parts to and from each other, 45 each pocket being provided with a spring controlled cage and bottom plate capable of being simultaneously opened and closed and of receiving an independent motion for applying pressure thereto, as set forth.
- 50 7. In a machine for applying labels to the ends of packets, the combination of framework having a table mounted thereon, a second set of framework in close proximity thereto having a rock shaft carried 55 by said second framework, an intermittently rotating drum having packet receiving pockets formed in its periphery at regular distances apart and having cages and centrally perforated bottom plates jointed thereto at 60 the ends of each pocket, means for opening, 65 closing and applying pressure to the cages and bottom plates, a label receiving box fixed at an angle to said table, a gum roller mounted in a box fixed to the table of the machine, oscillating arms mounted upon the 70 rock shaft above the table, each arm being provided with reciprocating gum pads, strippers and pins, and cams for intermittently operating the said pads, strippers and pins whereby the gum pads receive a film 75 of mucilage as they outwardly pass over the gum roller prior to taking up and removing a label from the magazine and depositing it in one of the said cages, as set forth.
8. In a machine for applying labels to the ends of packets, the combination of framework provided with bearings, a shaft mounted thereon and means for imparting an intermittently rotating motion thereto, a drum 80 fixed thereon having a number of pockets arranged in its periphery at regular distances apart and having label receiving cages and centrally perforated bottom plates hinged thereto opposite the end of each packet, a 85 table fixed to the framework of the machine and means comprising gum pads, strippers and pins for gumming and removing a label from a box fixed angularly to the table of the machine, pins fixed to the table adapted 90 to pass through the central holes in the bottom plates, separately operated gripping fingers mounted upon rock shafts carried in bearings fixed to the table and adapted to pass through recesses in the cage over the 95 bottom plate and to act in conjunction with the pins fixed to the strippers as and for the purposes herein set forth.
9. In a machine for applying labels to the ends of packets, the combination of an intermittently rotating drum having a number of pockets formed in its periphery at regular distances apart, each of said pockets having a cage and bottom plate hinged to each end, means for supplying the packets to the pockets and labels to the cages, an intermittently reciprocating ejector for removing a packet from a pocket after it has been end labeled, a chute for receiving the ejected packet and an oscillating platform for retaining the 100 label on the end of the packet as set forth.
10. In a machine for applying labels to the ends of packets, the combination of framework having a table mounted thereon, a second set of framework arranged in close 105 proximity thereto, a rock shaft carried by second framework, oscillating arms mounted on said shaft and having gum pads, strippers and pins fixed to their free ends, means for oscillating the said arms and operating 110 the gum pads, strippers and pins, a gum box fixed to the said table and having a roller mounted thereon, a label receiving box fixed at an angle to the table, an intermittently rotating drum having pockets formed in its 115 label on the end of the packet as set forth.
- 120 11. In a machine for applying labels to the ends of packets, the combination of framework having a table mounted thereon, a second set of framework in close proximity thereto, a rock shaft carried by second framework, oscillating arms mounted on said shaft and having gum pads, strippers and pins fixed to their free ends, means for oscillating the said arms and operating 125 the gum pads, strippers and pins, a gum box fixed to the said table and having a roller mounted thereon, a label receiving box fixed at an angle to the table, an intermittently rotating drum having pockets formed in its 130 label on the end of the packet as set forth.

periphery at regular distances apart, each pocket being provided at each of its ends with a spring controlled label receiving cage and centrally perforated bottom plate, said 5 cages and bottom plates being jointed to the drum and capable of being simultaneously opened and closed and separately pressed on to the ends of the packets, means for supplying the packets as they leave a packaging 10 machine to the pockets of the said drum, the delivery end of the chute which connects the packaging and labeling machines together being provided with an intermittent oscillat-

ing recessed hook ended lever for first receiving the packet in a vertical position, 15 means for turning the lever and packet over on to its side, a curved plate and transporting lever for receiving the packet from the hook ended lever and for transporting it into the pocket of the said drum, as set forth.

JAMES HADCOCK.
